UNITED STATES PATENT OFFICE.

FREDERICK J. FEINEMAN, OF ST. LOUIS, MISSOURI.

DESIGN FOR A BURIAL-CASKET HANDLE.

SPECIFICATION forming part of Design No. 34,865, dated July 30, 1901.

Application filed March 30, 1901. Serial No. 53,728. Term of patent 14 years.

To all whom it may concern:

Be it known that I, FREDERICK J. FEINEMAN, a citizen of the United States, residing in the city of St. Louis, in the State of Missouri, have invented and produced a new and original Design for a Burial-Casket or Coffin Handle, of which the following is a full, clear, and exact description, reference being had to the accompanying drawings, forming part 10 of this specification.

In the drawings, Figure 1 is a perspective view of a handle, showing my new design. Fig. 2 is a side elevation of the same.

As shown in the drawings, the leading or

material features of my design consist of a 15 vertical plate having a rounded top and a rectangular bottom and an arm upwardly and outwardly inclined from said plate and carrying at its outer end a cylindrical enlargement. 20

I claim as my invention—

The design for a burial-casket handle here-
in shown and described.

FREDERICK J. FEINEMAN.
